UNITED STATES PATENT OFFICE.

NEWTON J. SCOFIELD, OF NEW ORLEANS, LOUISIANA.

ADJUSTABLE SKIRT HANGER.

1,410,411.

Specification of Letters Patent. Patented Mar. 21, 1922.

Application filed August 23, 1921. Serial No. 494,611.

To all whom it may concern:

Be it known that NEWTON J. SCOFIELD, a citizen of the United States of America, residing at New Orleans, in the parish of 5 Orleans and State of Louisiana, has invented new and useful Improvements in Adjustable Skirt Hangers, of which the following is a specification.

The object of the invention is to provide 10 an efficient skirt hanger for display and like purposes whereby the dimensions thereof may be suited to those of the skirt with a view to supporting the latter to the best advantage from a display point of view, the 15 adjustability of the hanger being controlled by centrally located means or means arranged adjacent to or in connection with the supporting hook for the hanger, so that the extension or contraction is equalized in 20 opposite directions from the point of suspension without special adjustment or attention on the part of the operator to insure an even hanging of the garment; and with these objects in view the invention consists 25 in a construction and combination of parts of which a preferred embodiment is shown in the accompanying drawings, wherein:

Figure 1 is a perspective view of a hanger embodying the invention indicating in 30 dotted lines a skirt supported thereon.

Figures 2 and 3 are detail sectional views respectively at right angles to each other of the central supporting post.

Figure 4 is a detail view of the revolute 35 stem by which relative adjustment of the members of the hanger is effected.

Figure 5 is a similar view of the locking clip.

Figure 6 is a similar view of one of the 40 flange retaining washers.

Figure 7 is a perspective view of one of the frame members.

The hanger consists essentially of a normally horizontal, longitudinally extensible 45 frame 10 supported by a centrally located post 11 provided with means for relatively adjusting the members 10^a—10^b of the frame and for locking the same in their adjusted positions, and also having a suspending 50 hook or eye 12 by which the hanger may be suspended from a rod, nail or like means of suspension.

The frame members are of complementary 55 form and construction, each consisting of a single rod of wire doubled upon itself at an

intermediate portion of its length to provide a loop 13 having a shoulder 14 upon which the waistband of the skirt indicated in dotted lines at 15 may rest, the arms representing the terminal portions of the blank 60 being extended in substantial parallelism to provide upper and lower arms 15' and 16 with the corresponding arms of each member arranged in overlapping relation and extending through the supporting post 11. 65 The extremity of each arm is provided with a guide eye 17 to slidably embrace the corresponding arm of the other member.

The supporting post embodies a revolute 70 stem 18 having spaced toothed portions or pinions 19 and 20 for respective engagement with rack teeth 21 and 22 on the facing surfaces respectively of the upper and lower arms or elements 15' and 16 of the frame members to the end that the rotation of the 75 stem in one direction or the other will cause the simultaneous extension or contraction in opposite directions of the two members, to an equal extent. Threaded upon the upper end of the stem is a thimble 23 having 80 a neck or reduced portion 24 forming a seat for a ring 25 of the suspending hook or eye 12 to the end that the latter is swiveled on the thimble, and also threaded upon said stem is a lock or jam nut 26 serving to secure 85 the thimble against turning movement independently of the stem.

Correspondingly threaded upon the lower end of the stem is a nut 27 adjacent to which is arranged a lock or jam nut 28, and fitted 90 upon the stem adjacent to the planes respectively of the upper and lower arms or elements of the frame members are the reversely disposed washers 29 and 30 held in place by a spacing sleeve 31 fitted upon the 95 stem and interposed between said washers, the latter being provided respectively with upwardly and downwardly directed ears 29^a and 30^a which form lateral guides to prevent transverse displacement of the arms or elements which extend therebetween. The lock nuts 26 and 27 span respectively the intervals between the guide ears 29^a and 30^a of the washers 29 and 30 and complete 100 guides which retain the intermediate portions of the arms or elements of the extensible members in proper relation with the toothed pinion portions of the stem.

Fitted for axial sliding movement upon the thimble 23 is a locking member 31 pro- 110

vided with depending flanges 32 having seats or notches 33 which when the locking device is in its normal or depressed position straddle the upper arms or elements of the extensible frames, and as the interval between the flanges of the locking device corresponds with the width or diameter of the nut 26, the turning of the stem, to vary the relative adjustment of the members of the frame is prevented when the locking device is in its normal position. To permit of turning the stem as for example by manually turning the thimble 23, to adapt the frame to skirts having different waist measurements, it is necessary to raise the locking device 31 to disengage the seats or notches 33 from the upper arms or elements of the frame members, and when thus raised the locking device may be turned slightly to cause said seats or notches to engage the angles of the nut 26 so as to be held or temporarily locked in the inoperative position while the required adjustment of the frame members is being effected. Obviously it is only necessary to slightly raise and then turn the locking device and drop it into its normal position to effect the engagement of the seats or notches 33 with the upper arms or elements of the frame members to lock the stem against further adjustment.

The construction described provides for an extension of the frame to adapt it to properly support and display skirts having different waist or belt measurements while maintaining the supporting post or means of suspension in the center of the length of the apparatus so that the hanger when supported will occupy a horizontal position and thereby display the garment to the best advantage.

Moreover it will be obvious that the adjustment as to length of the supporting frame may be effected while the suspending hook or eye 12 is in engagement with a supporting object in view of the swivel connection between the thimble 23 and said hook or eye, and that in turning the thimble to effect an adjustment of the frame members the stem rotates within the spacing sleeve 31 and independently thereof and of the washers 29 and 30 while the nuts 26 and 27 turn with the stem.

Having described the invention, what is claimed as new and useful is:—

1. A skirt hanger having a frame consisting of relatively adjustable members provided with parallel arms arranged in overlapping relation, and a supporting post having guides for said arms or elements and provided with means for rotation to effect equal adjustment in opposite directions of said members.

2. A skirt hanger having a frame consisting of relatively adjustable members provided with arms arranged in overlapping

relation, and a supporting post having guides for said arms or elements and provided with means for effecting equal adjustment in opposite directions of said members, said means consisting of a revolvable stem having pinions engaging rackteeth on said arms or elements of the members.

3. A skirt hanger having a frame consisting of relatively adjustable members provided with parallel arms arranged in overlapping relation, and a supporting post having guides for said arms or elements, and means for effecting equal adjustment in opposite directions of said members, and consisting of a stem having pinions for engaging racks on said arms or elements of the members and guiding means straddling the corresponding arms or elements for holding them in operative relation with said pinions and having a swivel mounting upon the stem.

4. A skirt hanger having a frame consisting of relatively adjustable members provided with parallel arms arranged in overlapping relation, and a supporting post having guides for said arms or elements, and means for effecting equal adjustment in opposite directions of said members, and consisting of a terminally threaded stem having pinions for interposition between toothed corresponding arms or elements of the members, guiding elements consisting of washers having reversely directed ears to straddle and guide the corresponding arms or elements of the members and secure it in place by a spacing sleeve embracing the stem and interposed between said washers, and nuts threaded upon the terminal portions of the stem for respectively closing the spaces between the flanges or ears of said washers.

5. A skirt hanger having a frame consisting of relatively adjustable members provided with parallel arms arranged in overlapping relation, and a supporting post having guides for said arms or elements, and means for effecting equal adjustment in opposite directions of said members, and consisting of a revolvable stem having pinions for arrangement between and engagement with racks on the corresponding arms or elements of said members, and a locking device for securing the stem against rotary movement.

6. A skirt hanger having a frame consisting of relatively adjustable members provided with parallel arms arranged in overlapping relation, and a supporting post having guides for said arms or elements, and means for effecting equal adjustment in opposite directions of said members, and consisting of a revolvable stem having rack and pinion engagement with corresponding arms or elements of the said members and a locking device carried by the stem and hav-

ing an interlocking engagement therewith and with said arms or elements for securing the former against rotary movement.

7. A skirt hanger having a frame consisting of relatively adjustable members provided with parallel arms arranged in overlapping relation, and a supporting post having guides for said arms or elements, and means for effecting equal adjustment in opposite directions of said members, and consisting of a rotary stem having a rack and

pinion engagement with corresponding arms or elements of the frame members, a nut carried by the stem, and a locking device consisting of a plate having flanges spaced to engage said nut and provided with seats for selective engagement with corresponding arms or elements of the frame members and the angles of said nut. 15

In testimony whereof he affixes his signature. 20
